UNITED STATES PATENT OFFICE.

EDGAR B. SYMONS, OF EVANSTON, ILLINOIS, ASSIGNOR TO SYMONS BROTHERS COMPANY, OF EVANSTON, ILLINOIS, A CORPORATION OF SOUTH DAKOTA.

ADJUSTABLE HEAD FOR DISK CRUSHING MACHINES.

Application filed February 1, 1917. Serial No. 145,823.

To all whom it may concern:

Be it known that I, EDGAR B. SYMONS, a citizen of the United States, residing at Evanston, in the county of Cook and State 5 of Illinois, have invented a certain new and useful Improvement in Adjustable Heads for Disk Crushing Machines, of which the following is a specification.

My invention relates to improvements in crushing machines and has particular reference to what I prefer to call a horizontal sand machine of the crushing disc type. One object of my invention is to provide a new and improved arrangement for adjusting the distance between the crushing discs and thereby controlling the size of the output. Another object is to provide such adjusting means as will be rigid and accurate and will not change in their relation in wear. 20 Another object is to provide means for easily and conveniently changing such adjusting means and the adjustment made by them and means for supporting one part upon another while such adjustment is being made. 25 Other objects will appear from time to time in the specification.

My invention is illustrated more or less diagrammatically in the accompanying drawings, wherein—

30 Figure 1 is a section through the crushing head end of the machine;

Figure 2 is a plan view of a part of the machine, the hood shown in Figure 1 being omitted for the purpose of clearness:

35 Figure 3 is a section on the line 3—3 of Fig. 2; and

Figure 4 is a detailed plan view of one of the spacing shims.

Like parts are indicated by like characters 40 in all the figures.

The operating, driving and controlling parts of my crushing machine have been omitted from the drawings since they form no part of my invention. They have been 45 limited to the crushing head itself which is the subject matter of the invention.

A is a hollow main shaft rotatably mounted in the bearings A¹. It is flanged as at A², the flange containing the spherical bearing A³ in which is rotatably and oscillatably mounted a bearing ball or head A⁴ which supports the crushing disc A⁵ and which is carried upon a shaft A⁶ contained within the hollow shaft A. A⁷ is a hood mounted 55 on the frame A⁸, which frame also supports

the bearing A¹. The hood is adapted to catch the discharge from the crushing head. B is an annular crushing disc supporting plate. B¹ is a crushing disc rigidly and permanently mounted on that plate as shown. 60 This disc is open at the center to permit the feed chute B² to discharge therethrough into the lenticular crushing zone. The flange A² and the plate B are both perforated about their outer peripheries and bolts B³ extend 65 through said perforations. These bolts are spaced comparatively close together as shown in Figure 2 and they rigidly tie the flange and plate together about their peripheries. Mounted on these bolts are spacing sleeves B⁴. The deflector plates B⁵, B⁶ are perforated so that the bolts B³ may pass 70 through them. They are located one on either side of the sleeve B⁴. The purpose is to assist in guiding the material as it is 75 discharged centrifugally from the periphery of the lenticular crushing zone and to prevent to as great an extent as possible the discharge of the material along lines inclined to the plane of the crushing zone. The sleeves 80 B⁴ besides acting as spacing sleeves prevent the material discharging from a crushing zone.

B⁷ is a nut adapted to fit upon and cover the projecting thread of the holding bolt B³ 85 to protect it from battering by the impact and deflected material discharged from the crushing zone.

C, C¹, C², C³, and C⁴ are adjusting and spacing shims of different thickness. They 90 are each of them slotted as shown at C⁵ in Figure 4, this slot being provided so that these shims may be dropped over and moved from the bolts without withdrawing the bolts, the idea being that when it is necessary to change the distance between the crushing discs either because they have worn down or because it is desired to change the size of the product, these shims may after 95 the bolts have been loosened be withdrawn 100 without completely withdrawing the bolts and thus removing the support for the outer crushing disc.

These shims are relatively short and the shims surrounding one bolt do not come in 105 contact with the shims surrounding another and the spacing ring B⁶ is thus doubly necessary since it covers the gap between adjacent groups of shims and presents a smooth surface for the contact of flying particles 110

which may be deflected out of their normal rectilinear path. Each of these spacing shims is perforated as at C⁶ and the ring B⁶ is also perforated as well as the plate B near each of the holding bolts so that the holding pin C⁷ may be passed through the entire group. This pin is held in place by a cap C⁸ enclosing the head C⁹ and this cap is held down by a cap screw C¹⁰, the purpose of this arrangement being to permit a ready withdrawal of this pin when it is desired to remove the shims or hold the machine in position while in operation and the purpose of the pin itself is to hold each group of shims in position before the bolts are tightened up. It is understood that in adjusting the crushing head each bolt will be loosened. The shim will be added or withdrawn until the proper adjustment can be made and the bolts will then be tightened up. It becomes necessary, however, to rotate the crushing head while this adjustment is taking place and before the bolts are tightened and the pin co-operating with the long slot in each shim prevents the shims dropping away from the bolt when upside down.

It will be evident that while I have shown in my drawings an operative device, still many changes might be made both in size, shape and arrangement of parts without departing materially from the spirit of my invention, and I wish, therefore, that my drawings be regarded as in a sense diagrammatic.

The use and operation of my invention are as follows:-

It invariably develops in connection with my type of rotating disc crushing machines that in operation it becomes from time to time necessary to change the distances between the members supporting the two crushing discs. This change is necessitated both by the wear of the discs which must be brought from time to time closer together to compensate for their wearing if a uniform product is to be obtained and by the desire occasionally developing for a different sized product. The fullest mentioned requirement, that is to say adjustment for wear always calls for a decrease of the distance between the supporting members, The second requirement, that is to say for a varying sized product sometimes calls for a decrease and sometimes for an increase.

It will be noted that the two supporting members are held together by a series of holding bolts which tend to force the parts together and clamp between them a series of bolt engaging sleeves together with spacing shims. These sleeves are mounted on the bolts and are never removed. The spacing shims, however, are removable and are arranged as shown in different sizes so that by adding or taking away any desired adjustment within a reasonable range may be made.

This adjustment is made in the following manner. The enclosing hood or housing is opened and the two hinged halves allowed to drop down thus exposing the crushing head. The lock nuts are then manipulated to release the holding nuts and these nuts are turned so as to permit the head parts to be separated. It is only necessary to turn these nuts a short distance sufficient to release the pressure upon the shims and sufficient to permit the holding pins which hold the shims in position to be withdrawn. When this is done the shims are removed or others are inserted, the holding pins are replaced, the nuts are screwed up on the bolts to jam the parts together and the lock nuts are then put in place.

It will be noted that the lock nuts are provided with sleeves projecting upwardly and closing the ends of the bolts. This is for the purpose of protecting the threads from battering by the flying particles as they are discharged under centrifugal force from the crushing head. Obviously the power of the screw and nut is sufficient to draw the cleat supporting parts together after the adjustment has been made. Since this power is not available for separating the parts to release the pressure on the shims other means such as are found in any shop may be used, a lever or a hammer or a jack or any other suitable arrangement.

By this arrangement it will be understood that the plate holding the heads may be easily and conveniently adjusted toward one another and that by holding these special shims in reserve any desired adjustment may be made. The discharge of material to one side is prevented so far as possible by the covering ring and obviously there will be no tendency of material to bank up between the ends of the adjacent shims because centrifugal force will prevent.

There will be no wear on the shims themselves and no possibility of any material getting between adjacent shims because of the fact that the powerful holding screws are amply powerful to clamp the parts together and lock the shims in position and prevent any rocking of one cleat, that is of one disc supporting part with respect to the other.

I claim:

1. In a crushing machine a crushing head comprising two parallel supporting plates, means for rigidly and adjustably fastening them together, comprising a series of spacing sleeves between them, holding bolts passing through them and the sleeves, and a series of removable shims interposed between the plate and the sleeves, and crushing discs located between the plates, the shims being slotted so as to straddle the bolts there being one group of shims for each bolt, means independent of the holding

bolts for holding the shims in position until they can be tightened up.

2. In a crushing machine comprising two opposed supporting plates, a rotating crushing head, a pair of crushing discs within the head, and means for operating them to crush material while they rotate, a hood surrounding the head and adapted to contain the material as it is discharged from between the 10 discs by centrifugal force, holding bolts adapted to lock the supporting plates together, and mounted in the head, and means carried by said bolts for protecting their threads against battering by the impact 15 of deflected discharged material from between the discs.

3. In a crushing machine comprising opposed compression members, adjustable spacing means between the compression 20 members, comprising bolts passing through such compression members, spacing sleeves surrounding said bolts, adjusting shims removably supported on each bolt and means independent of said bolts for holding the 25 shims against rotation thereabout during adjustment.

4. In a crushing machine comprising opposed compression members, adjustable spacing means between the compression 30 members, comprising bolts passing through such compression members, spacing sleeves surrounding said bolts, adjusting shims removably supported on each bolt and means independent of said bolts for holding the 35 shims against rotation thereabout during adjustment, comprising pins adjacent each bolt connecting one of said compression members and the shims.

5. In a crushing machine comprising opposed compression members, adjustable spacing means between the compression members, spacing sleeves surrounding said bolts, adjusting shims removably supported on each bolt and means independent of 40 said bolts for holding the shims against rotation thereabout during adjustment, comprising pins adjacent each bolt, connecting 45

one of said compression members and the shims and means for preventing the displacement of said pins.

50

6. In a crushing machine comprising opposed compression members, adjustable spacing means between the compression members, spacing sleeves surrounding said bolts, adjusting shims removably supported on each bolt and means independent of said bolts for holding the shims against rotation thereabout during adjustment, comprising removable pins adjacent each bolt, connecting one of said compression members 60 and the shims and means for preventing the displacement of said pins, comprising members secured to the compression members and removably covering the ends of said pins.

65

7. In a crushing machine comprising opposed compression members, adjustable spacing means between the compression members, comprising bolts passing through such compression members, spacing sleeves 70 surrounding said bolts, adjusting shims removably supported on each bolt and means independent of said bolts for holding the shims against rotation thereabout during adjustment, and a deflector plate covering 75 the shims and located between them and the discharge area about the edge of the crushing members.

8. A disk type crusher embodying two relatively movable heads, one of said heads 80 having a peripheral shoulder, means for holding said heads in adjusted spaced relation comprising an abutment member spanning the space between said heads and adjusting means interposed between said abutment member and one of said heads and protected by said shoulder.

In testimony whereof, I affix my signature in the presence of two witnesses this 23rd day of January 1917.
